UNITED STATES PATENT OFFICE

2,509,797

VENTILATOR

Opal A. Barber, Oklahoma City, Okla.

Application October 1, 1946, Serial No. 700,491

2 Claims. (Cl. 98—68)

1

My invention relates to a ventilator for dwellings, office buildings, barns, stables, and houses in general needing proper ventilation and outlet for stale air, delivered from the roof into the open air. This invention is more efficient than ordinary ones now in general use.

This ventilator is of very simple construction and, as a consequence, can be manufactured at low cost of inexpensive material now available.

One object of the invention is to create suction action from the outside air to aid in drawing out air passing through the ventilator from the room or building where the device has been set up.

For this purpose the hood, which is of the general elbow shape now in use for this type of ventilator and set in the wind direction by a vane, is provided with an adjunct on the wind-side of the hood in order to lead the exterior air from the rear, above and around it to the front or exit of the hood, thereby creating a partial vacuum at the hood nozzle to increase the speed of the air current drawn from the inside of the building.

With these and other objects in mind, the invention will be understood from the following description with the aid of the attached drawing showing one embodiment of the invention.

Figure 1 is a side elevation of the ventilator;

Figure 2 is a front elevation of Figure 1; and Figure 3 is a vertical section taken on a plane along line 3—3 of Figure 2.

In the drawing, like reference numerals relate to the same details in the different views.

Reference numeral 10 denotes the roof of a building upon which the ventilator is erected.

A vent base 11 is positioned in a suitable place on the roof. This base has the shape of a conic frustum with bottom flange 12 bolted down tightly on the roof over the air vent in order to conduct the air current out through the elbow shaped hood 13 and its nozzle 14 in the direction of arrow X. The hood 13 is of elbow shape and preferably cylindrical, with its nozzle cut backward, slanting against its horizontal axis thus forming an elbow with its vertical skirt 15, fitting around the cylindrical top 16 of the base 11.

The entire hood 13 is supported on an axial, vertical, hollow shaft 17, which is rigidly secured to the horizontal portion of the hood as by braces 18. The shaft 17 seats in a socket bearing 19 resting on a ball bearing 20 and running in oil supplied through the hollow shaft 17 from the cup 21 at the top thereof.

The socket bearing 19 has the form of a deep cup which is secured in the cylindrical top 16 as by braces 22. Thus the entire weight of the ventilator hood is supported on a ball bearing 20 in the socket 19.

At 25 is shown a vane which is secured on top of the hood 13 by stays 26 in the vertical plane of the axis thereof.

Lastly, but of great importance is the "bullet nose" 27 which is of conical shape and attached on the rear or wind-side end of the horizontal

2

top portion of the ventilator hood 13 and in axial alignment therewith. The base of this cone or "bullet nose" is of the same diameter as that of the horizontal hood top portion 13, so that air current hitting said cone, becomes deflected to follow the top and sides of the hood, and when reaching the nozzle, causes suction, aiding in withdrawing air from the vent base 11.

The rear wall 28 of the horizontal portion of 10 the hood 13 is arched to provide a smooth path for the outgoing air, without obstructions changing from vertical to horizontal direction.

It is to be understood that the invention as 15 herein disclosed may be varied from the details described and shown without departure from the spirit of the subjoined claims.

What is claimed is:

1. A ventilator comprising a hollow conical base, a cylindrical extension rising from the top 20 end of said base, an elbow having one of its legs seated over the top end of said extension, a tubular bearing centered within said extension and having a closed rounded lower end, a spider mounted within the tubular extension and sup-

25 porting said bearing in place, a shaft seated in and rising from said bearing and having its top end secured at the top of said elbow, a vane rising from the top side of the horizontal leg of said elbow, a cylindrical member extending from 30 said elbow in line with and opposite from said horizontal leg, said cylindrical member having the same outside diameter as said leg, and a conical cap closing the outer end of said cylindrical member.

35 2. The invention as defined in claim 1 wherein said shaft is hollow and comprises a length of metal tubing and having its top end passed through the top sides of said elbow and said cylindrical member and outwardly flared into en-

gagement with the wall of the latter, and a ball 40 seated within the lower end of said shaft, said shaft supporting the lower end of said bearing, said shaft being adapted to receive a lubricant in its top end to convey the same to said bearing.

OPAL A. BARBER.
